US0D1102562S

(12) **United States Design Patent** (10) **Patent No.:** **US D1,102,562 S**
Paris et al. (45) **Date of Patent:** **** Nov. 18, 2025**

(54) **FLUIDODYNAMIC ACTUATOR**

- (71) Applicant: **AIR TORQUE S.P.A.**, Costa di Mezzate (IT)
- (72) Inventors: **Ignazio Paris**, Grumello del Monte (IT); **Antonio Marinoni**, Grumello del Monte (IT)
- (73) Assignee: **AIR TORQUE S.P.A.**, Costa di Mezzate (IT)
- (**) Term: **15 Years**

(21) Appl. No.: **29/839,993**(22) Filed: **May 25, 2022****Related U.S. Application Data**

- (62) Division of application No. 29/698,969, filed on Jul. 22, 2019, now Pat. No. Des. 960,327.

(30) **Foreign Application Priority Data**

Jan. 22, 2019 (EM) 006081089

Primary Examiner — Selina Sikder*(74) Attorney, Agent, or Firm* — CANTOR COLBURN LLP(57) **CLAIM**

The ornamental design for a fluidodynamic actuator, as shown and described.

DESCRIPTION

FIG. 1 is a perspective view of a fluidodynamic actuator showing my new design;
 FIG. 2 is a front view thereof;
 FIG. 3 is a rear view thereof;
 FIG. 4 is a left side view thereof;
 FIG. 5 is a right side view thereof;
 FIG. 6 is a top view thereof;
 FIG. 7 is a bottom view thereof;
 FIG. 8 is a perspective view thereof, taken from below;
 FIG. 9 is a perspective view of the fluidodynamic actuator in another embodiment;
 FIG. 10 is a front view thereof;
 FIG. 11 is a rear view thereof;
 FIG. 12 is a left side view thereof;
 FIG. 13 is a right side view thereof;
 FIG. 14 is a top view thereof;
 FIG. 15 is a bottom view thereof; and,
 FIG. 16 is a perspective view thereof, taken from below.

1 Claim, 14 Drawing Sheets(56)
